UNITED STATES PATENT OFFICE.

HENRY PILLING, OF CHORLTON-CUM-HARDY, ENGLAND.

CYLINDER FOR UNIFLOW STEAM ENGINES.

1,268,801.

Specification of Letters Patent.

Patented June 4, 1913.

Application filed March 4, 1913. Serial No. 220,374.

To all whom it may concern:

Be it known that I, HENRY PILLING, a subject of the King of Great Britain, residing in Chorlton-cum-Hardy, England, have invented certain new and useful Improvements in Cylinders for Uniflow Steam-Engines, of which the following is a specification.

This invention relates to uniflow steam engines of the type in which for greater facility of construction, assembling or repair the cylinder is built up of separate parts or sections and consists essentially of an improved construction of cylinder of this type.

15 In uniflow steam engines, particularly those of large size, the question of the cylinder construction is a very important one, inasmuch as the high initial loading on the piston, due to the high ratio of expansion in this class 20 of engine, makes it difficult to provide adequate cylinder strength at the center of the cylinder barrel, where so much metal is necessarily cut away to form the exhaust slots.

25 A second point of importance in condensing uniflow engines, is the provision of a sufficiently small clearance at the end of the cylinder, in order that the compression pressure may rise, as far as may be, up to the initial pressure. For example, if the engine is working with a good vacuum giving, say, one and a half pounds back pressure only, then, to get back to an initial steam pressure of, say, 150 lbs. per square inch absolute, 30 the compression ratio must be 100 to 1, which in practice requires about one and a half per cent. clearance only. Now, it is very difficult to get this small clearance. In order to provide maximum longitudinal 35 strength in the cylinder and to obtain the requisite area of the exhaust slots, these slots have to be made long and narrow, so as to leave sufficient circumferential metal to give the requisite strength and carry the 40 steam load of the engine. It would obviously be an advantage if the slots could be short and wide, as thereby equal steam area could then be provided, and at the same 45 time a rather greater proportion of the 50 length of the cylinder would be rendered available for the purposes of compression.

A third point in uniflow engines which presents a difficulty is that when running the two inlet ends are hot zones, and the 55 center is a cold zone; therefore, it is necessary, in order to insure a parallel working

cylinder, that the barrel shall be bored in the first place taper fashion, the two ends being somewhat smaller than the center, the difference being so calculated that when the 60 cylinder is heated, the parallel form is obtained. This boring of the cylinder with a double taper is a very difficult matter in actual practice.

Again, a fourth difficulty is that, inasmuch as in many cases it is necessary to provide a jacket at the hot zone end of the cylinders of uniflow engines a complexity of construction is introduced which causes great difficulty to the iron founder, this complexity being a very serious obstacle to the manufacture of very large cylinders in "one piece" castings.

The present invention is designed to provide means for overcoming these objections 75 and at the same time to provide a construction of cylinder which, whether jacketed or otherwise, shall be as free as possible from casting strains and manufacturing difficulties, and shall also facilitate repair and the 80 renewal of any part in case of accident.

The invention will be fully described with reference to the accompanying drawings, which show by way of example a form of cylinder constructed according to the invention.

Figure 1 is a sectional elevation of a cylinder constructed according to the invention;

Fig. 2 is a section on line 2—2 of Fig. 1.

According to the present invention the cylinder A is made in two parts, the joint being preferably formed in the middle of the length of the cylinder where the exhaust takes place. The ends a, a' of the 95 two parts of the cylinder A which are to abut against each other are formed with peripheral extensions B having chambers or recesses therein, which when brought together form between them an exhaust chamber or passage C surrounding the cylinder A for the outlet of the exhaust steam, a suitable connection being made thereto for its escape. The two parts of the cylinder are secured together by bolts D passing 100 through the peripheral extensions or flanges B in well known manner and also preferably by special "through" bolts E set as close to the cylinder barrel as may be in order to transmit, in as direct a line as possible, the 105 longitudinal forces passing along the barrel. The adjacent ends of the two parts of the

actual cylinder barrel are so constructed as to form between them, as shown, a number of passages F leading from the cylinder to the main exhaust passage C. A heating 5 jacket G is shown at one end of the cylinder for the purpose of maintaining a high and steady temperature in the hot zone of the cylinder. When employed, such jackets are, of course, provided at both ends of the cylinder.

10 I claim as my invention:

A cylinder for uni-flow steam engines comprising two sections forming the respective ends of the cylinder and having 15 their adjacent ends in abutting engagement and shaped to form an exhaust port between them, said sections having circumferentially extending flanges cast integrally

thereon adjacent to their abutting ends and projecting outwardly from their peripheries, said peripheral flanges being shaped to form between them a peripheral exhaust passage in communication with said exhaust port, and means directly connecting said circumferential flanges on the sections and 25 operative to draw the adjacent ends of said sections into abutting engagement and to maintain said ends of the sections in abutting engagement.

In testimony whereof I have signed my 30 name to this specification in the presence of two subscribing witnesses.

HENRY PILLING.
